UNITED STATES PATENT OFFICE.

EDWIN M. ROSENBLUTH, OF PHILADELPHIA, PENNSYLVANIA.

LANTERN.

SPECIFICATION forming part of Letters Patent No. 606,028, dated June 21, 1898.

Application filed November 6, 1897. Serial No. 657,590. (No model.)

To all whom it may concern:

Be it known that I, EDWIN M. ROSENBLUTH, a citizen of the United States, residing in the city and county of Philadelphia, in the

5 State of Pennsylvania, have invented certain new and useful Improvements in Lanterns, of which the following is a specification.

My invention relates to vehicle and other lamps or lanterns, and especially to the reflecting devices or plates ordinarily mounted in and carried by them.

As is well known, in the continued use of lanterns, the reflectors receive deposits of soot and other matters which impair their capacity for reflection, and it is therefore desirable to so mount them that they may be readily removed for the purpose of being cleaned and polished.

It is, moreover, a desideratum that reflectors thus removably mounted within lanterns, should be supported in position in such manner as not only to be maintained against displacement but also as to preclude the rattling of the parts in the oscillation to which the lantern in the travel of the vehicle is subjected.

My invention aims to provide, in connection with vehicle lanterns and their reflectors, reflector-holding or supporting devices of such character as to support the reflectors in position in the lanterns with such firmness as to preclude their displacement or rattling, and as, together with the reflector, to be easily and readily removable.

In the accompanying drawings I show and 35 herein I describe, forms of devices conveniently and alike embodying my invention, the particular subject-matter claimed as novel being hereinafter definitely specified.

In the accompanying drawings I illustrate 40 my improvements as employed in connection with a vehicle lantern invented by me and forming the subject-matter of Letters Patent No. 561,816, dated June 9, 1896, and also of an application for United States Letters Patent, filed September 24, 1896, as Serial No. 606,837.

It is, however, to be understood that my improvements herein set forth are applicable in connection with vehicle and other lanterns 45 of any character, and particularly also those in which the combustion chamber is vertically disposed.

In the accompanying drawings,

Figure 1 is a central, sectional, elevational view of a lantern equipped with a preferred 55 form of my improvements.

Figure 2 is a view in perspective of the reflector shown in Figure 1 removed from the lantern.

Figure 3 is a view in face elevation of the 60 reflector shown in Figures 1 and 2.

Figure 4 is a front elevational view of the lamp and contained reflector shown in Figure 1, the casing of the combustion chamber being shown in section in the plane of the dotted line 4-4 of said Figure 1.

Figure 5 is a view in perspective of a reflector embodying a fundamental form of my improvements; and

Figure 6 is a similar view of a reflector embodying a modified form of my improvements, in which the ends of the arms of the holder are upturned to adapt the device to be introduced within a top-opening, vertically-disposed, combustion chamber.

75

Similar letters of reference indicate corresponding parts.

Generally stated, my invention comprehends the provision of a spring holder of substantially the character herein described and 80 claimed, adapted to removably secure a reflector in place within a lantern.

In the drawings,

A is the combustion chamber of the vehicle lantern,—which in the form shown in 85 Figures 1 and 2 happens to be horizontally-disposed.

B is the lamp chamber of said lamp, which serves to contain the lamp b, the wick tube of which projects within the combustion 90 chamber; and C is the cap or chimney of the lantern, disposed above the combustion chamber which opens into it through the chimney throat c.

D is a supporting device by means of which 95 the lantern may be connected to the vehicle.

E is a swinging door, mounted in hinged relationship with respect to the flaring mouth of the combustion chamber, and provided with the ordinary lens e; while F is a jewel-provided light opening in the rear end wall 100 of the combustion chamber.

G is the reflector, which may, as stated, be of any desired character.

In Figures 1, 2, 3, and 4, of the drawings this reflector is shown as provided with a central aperture g in line with the rear light opening F , to render the light visible from the rear of the lantern,—and said reflector is also shown as provided with a glass protecting plate g^x , disposed in front of its silvered or reflecting face and seated behind forward and inwardly inclined circumferential lips g' mounted upon or formed as integral continuations of the body of the reflector.

The glass protecting plate may be conveniently secured beneath said lips g' by means of a spring annulus G^x disposed in front of said protecting plate and self-retaining in position by its expansion against the inner face of said lips.

The engagement of the annulus within the lips will serve to normally retain the protecting plate securely in position, while the removal of the annulus and plate to permit of the cleaning of the face of the reflector may be conveniently effected by compressing or forcing together the outwardly turned ends g^2 of the annulus.

The holder H , which may be made in a great variety of forms to suit the varying requirements of the different forms of combustion chambers of the numerous styles of lamps manufactured, is preferably formed as a multi-armed single-piece wire structure of the general form indicated in Figures 1, 2, 3, and 4, that is to say embodying four arms $h' h^2 h^3 h^4$ all extending forwardly from the reflector, and all slightly divergent or having an outward spring or set, to adapt them to retain their hold against the wall of the combustion chamber within which they are entered and slightly compressed.

I prefer to so arrange the holder that, when the reflector has been seated in its proper position, the arms, or one or more of them, will be seated or engaged within any suitable recess aperture or depression of the combustion chamber in order to positively lock the reflector in position,—and to that end, in the embodiment of my invention shown in Figures 1, 2, 3, and 4, the arms $h^2 h^3$ are shown as prolonged and merged into each other at their front extremities, and as so fashioned as to constitute a locking projection h^5 , which is so located and arranged with reference to the other parts of the lantern that when the reflector is mounted in the combustion chamber said locking projection will extend up within the throat of the chimney and by contact with the forward edge of said throat prevent any undue forward movement of the reflector.

The bodies of the arms $h' h^2 h^3 h^4$ preferably extend somewhat to the rear of the reflector, and are bent to form return bends h^6 , which project rearwardly from said reflector, and, by contact with the rear wall of the combustion chamber, serve to maintain the reflector in proper position with relation to said

rear wall and preferably in such position that an air chamber or space is formed behind said reflector,—and which also serve to impart to the arms the desired spring set.

The holder may be conveniently secured to the reflector by the engagement of the lengths $h^7 h^8$,—which respectively connect the return bend of the arm h' with the return bend of the arm h^2 , and the return bend of the arm h^3 with the return bend of the arm h^4 ,—within lips or clips h^9 conveniently constituted by outwardly and rearwardly curved tongues mounted on or formed as integral continuations of the marginal portion of the reflector.

It will also be understood that the arrangement of holder described, in which four arms, all formed from one continuous strand of metal and each provided with a projection h^6 , and the whole secured to the reflector by the clips h^9 , are employed,—is a preferred arrangement merely, and that these details of construction and arrangement may be omitted or varied at will, without departure from the spirit of my invention.

Thus, in Figures 5 and 6, I have represented the very simplest types of embodiment of my invention, in which the arms are separate, directly attached to the reflector, not provided with any locking projection, and which operate to retain the reflector in position wholly by virtue of the friction of their separate expansive contact against the walls of the combustion chamber.

To remove the reflector represented in the first four figures of the drawings, from the combustion chamber, it is only necessary to open the door of the chamber, to grasp and deflect the arms $h^2 h^3$ to carry the locking projection out of engagement with the chimney throat, and, retaining said locking projection deflected, to draw the holder and reflector out through the open door.

In returning the reflector to position, it is to be merely forced rearwardly through the combustion chamber, until the bends h^6 encounter the rear wall of the chamber, and the locking projection engages with the chimney throat.

Having thus described my invention, I claim—

1. In combination, a lamp, embodying a combustion chamber having an opening formed in its wall, a reflector, and a holder for said reflector which consists of wire spring arms at their inner ends connected with the reflector, and a locking projection formed as part of said reflector holder and adapted to engage in said opening in the wall of the combustion chamber, substantially as set forth.

2. In combination, a lamp, embodying a combustion chamber having an opening formed in its wall, a reflector, and a holder for said reflector which consists of wire spring arms at their inner ends connected with the reflector, and a locking projection formed as part of said reflector holder and as a continuation

of two of said arms and adapted to engage in said opening in the wall of the combustion chamber, substantially as set forth.

3. In combination, a lamp, a reflector, and a holder for said reflector which consists of a series of spring arms at their inner ends connected with the reflector, and as to their bodies extending away from it, and at its rear formed with return bends which are adapted to make contact with the rear wall of the combustion chamber, substantially as set forth.

4. In combination, a lantern or lamp, a reflector, and a holder for said reflector which consists of a series of wire arms disposed in substantial parallelism with the axis of the reflector, extending to the front and rear of said reflector, at the rear provided with return bends which are connected to the marginal portion of the reflector, and at the front diverging from each other, substantially as set forth.

5. In combination, a lantern or lamp, a reflector, and a holder for said reflector which consists of a series of wire arms disposed in substantial parallelism with the axis of the reflector, extending to the front and rear of said reflector, at the rear provided with return bends which are connected to the marginal portion of the reflector, and at the front diverging from each other, and the front or forward extremity of one of which is equipped with or formed into a locking projection adapted in the predetermined set of the parts to expand to place within a suitable recess in the body of the lantern, substantially as set forth.

In testimony that I claim the foregoing as my invention I have hereunto signed my name this 4th day of November, A. D. 1897.

E. M. ROSENBLUTH.

In presence of—

SAMUEL MYERS,
G. INSLEE JONES.
